UNITED STATES PATENT OFFICE.

GEORGE W. DICKEY AND THOMAS A. HARDING, OF DES MOINES, IOWA,
ASSIGNORS TO THE DICKEY AUTOMATIC CAR-COUPLER COMPANY,
OF SAME PLACE.

CAR-COUPING.

SPECIFICATION forming part of Letters Patent No. 519,700, dated May 15, 1894.

Application filed January 15, 1894. Serial No. 497,005. (No model.)

To all whom it may concern:

Be it known that we, GEORGE W. DICKEY and THOMAS A. HARDING, citizens of the United States of America, residing at Des Moines, in the county of Polk and State of Iowa, have invented a new and useful Car-Coupling, of which the following is a specification.

Our invention relates to the master-car-builders' type of automatic car couplings and to that species in which a jaw is pivotally connected with a draw head and locked in a closed position, by means of a pin, and also moved outward into an open position by the movement of the pin as required to unlock the jaw.

Our object is to prevent the damage and breaking incident to this class of car couplers by the force of the impact of two mating jaws when brought violently together by the motions of cars and a train on a track and also to guard the locking pin in the cavity of the draw head from contact with a coupling link when the jaw is closed and to prevent anything from getting into the cavity of the draw head and in rear of the rear end of the jaw when the jaw is in an open position.

Our invention consists in the construction, arrangement and combination of a draw head, a jaw and pin guard and a jaw-locking and jaw-operating pin as hereinafter set forth, pointed out in our claims and illustrated in the accompanying drawings, in which—

Figure 1 is a bottom view of the upper half section of the draw head showing the under side of the pivoted jaw and the jaw in a closed position and locked by means of the pin and the pin protected by means of the guard integral with the jaw. Fig. 2 is a top view of the lower half section of the draw head and also a top view of the pivoted jaw in a closed position and the upper end portion of the locking pin cut off on a level with the face of the jaw and the top edge of the guard integral with the jaw. Fig. 3 is a sectional view through the drawhead, the jaw and the guard on the line xx in Fig. 1 and the locking pin complete and in position as required to lock the jaw. Fig. 4 is a sectional view of the

draw head, the jaw and pin guard on the line zz shown in Fig. 2 and the locking pin complete and in position as required to lock the jaw in its closed position. Fig. 5 is a perspective view showing the complete invention 55 and the jaw in a closed and locked position. Fig. 6 is a rear face view of the jaw in an inverted position showing the shoulder on the inner end portion and bottom side adapted to engage a corresponding shoulder in the 60 bottom portion of the cavity in the draw head, the rear end of the jaw adapted to engage the wall of the cavity as clearly shown in Fig. 2 and also showing the pin guard extended beyond the rear end of the jaw. 65 Fig. 7 is a view showing the straight back of the locking pin and the lower lateral projection that engages the inclined lower face of the rear end of the jaw as required to open the jaw when the pin is lifted. 70

The letter A designates a draw head that has a cavity adapted for receiving and supporting the jaw pivoted thereto.

A^2 is an angular-shaped portion of the cavity into which the upper portion of the rear 75 end of the jaw enters to abut against the wall of the cavity and to be supported thereby, as shown in Fig. 2, when the jaw is subjected to violent rearward pressure.

A^3 , shown in Fig. 4, is a shoulder on the 80 under side and rear portion of the cavity adapted to engage a shoulder on the under side of the jaw to aid in supporting the jaw when subjected to rearward pressure occasioned by impact when in practical use or 85 when subjected to the force of a falling weight to test the coupling.

B is a jaw fitted and pivoted to the forward extension of the jaw in such a manner that its rear end portion will extend into the cavity in the draw head as required to be locked fast therein by means of a pin. The upper portion and rear end B^2 of the jaw is adapted to enter the angular corner A^2 of the cavity and B^3 is a shoulder on the under side of the 95 jaw adapted to engage the shoulder A^3 on the under side of the cavity as clearly shown in Fig. 4.

B^4 represents an inclined bottom portion of the rear end of the jaw adapted to be en- 100

gaged by the jaw locking and jaw-operating pin as required to move the jaw into an open position by lifting the pin to unlock the jaw.

5 C is a pin guard integral with the rear end of the jaw and adapted in shape to cover and protect the pin and also to aid in supporting the jaw from the force of rearward pressure when in practical use and subjected to the impact of a mating jaw on a car in a moving 10 train and also to cover the approach to the cavity in the draw head and prevent the end of a coupling link from entering.

D is a pin adapted to be passed down through a pin hole in the upper part of the 15 wall of the cavity in the draw head and, after making about one eighth of a revolution, to have its lower portion pass through another pin hole in the lower portion of the draw head, as shown in Figs. 3 and 4, and as required to lock the jaw in a closed position 20 and also at the same time prevent the pin from accidentally jumping and escaping upward when the car and coupling are subjected to jarring and concussion.

25 D² is a lateral projection, below the head of the pin D, that is fitted to enter the space between the guard C and the rear end of the jaws, as clearly shown in Fig. 2, to lock the jaw in its closed position. The bottom of the 30 projection D² is inclined in such a manner that when the rear top edge B² of the jaw comes in contact therewith in its rearward or inward movement it will lift the pin D and allow the jaw to abut against the angular wall A² and when the jaw is thus admitted into the cavity in the draw head the pin D will drop and lock the jaw in position as clearly 35 shown in Fig. 2.

D³ is a lateral projection at the lower portion 40 of the pin D and stands at an acute angle relative to the projection D² so that the pin must be turned about an eighth of a revolution in its up-and-down motions through the pin holes in the draw head. The top face 45 of the lower projection D³ is an inclined plane adapted to engage the inclined surface B⁴ on the under side of the rear portion of the jaw B as required to push the jaw into an open position, as indicated by dotted lines in Fig. 1, 50 whenever the pin is lifted to unlock the jaw.

From the foregoing description of the construction and function of each part the practical operation of our invention is obvious. It is also obvious that any blow or rearward 55 pressure upon the jaw B will be distributed to different points by means of the angular jaw supports A², and the shoulder A³ in the draw head and the end B² and the shoulder B³ of the jaw B and the pin D, as required to prevent 60 the jaw from breaking or of any undue rearward movement and the bending or breaking of the pivotal pin F that connects the jaw with the forward extension of the draw head. It is also obvious that when the jaw B is in 65 an open position, as indicated by dotted lines in Fig. 1, the guard C will prevent the front

part of a mating jaw from passing rearward and getting into contact with the rear end B² of the open jaw, or wedging fast between the rear end of the open jaw and the drawhead. 70

We claim as our invention—

1. In a car-coupling of the species described, a jaw adapted to be pivoted to a draw head and having a rearward extension adapted to enter an angular space in the cavity of a draw head to abut against the wall of said cavity and a shoulder on the under side of said extension adapted to abut against a corresponding shoulder in the bottom of the same cavity, in combination with a draw head 80 having a cavity adapted to admit the rear extension of the jaw and to support it in the manner set forth, for the purposes stated.

2. In a car-coupling the jaw B having a rear extension terminating in an angular end B² 85 and provided with a shoulder B³ on its under side in combination with a draw head A having an open cavity and angular space A² adapted to admit the end B² of the jaw and a shoulder A³ adapted to engage the shoulder B³ of the jaw, in the manner set forth for the purposes stated.

3. In a car coupling, the jaw locking pin D having a projection D² and the bottom face of the projection inclined to be engaged and 95 lifted thereby by means of a jaw, and a projection D³ inclined on its top face to engage and move a jaw, in combination with a draw head and a jaw pivoted thereto, as and for the purposes stated.

4. In a car-coupling, the combination of a pivotal jaw having an integral pin guard C and inclined face on its under side, and a jaw locking pin D having a projection D² at its upper portion and an inclined face at the 105 bottom thereof and a projection D³ at its lower portion provided with an inclined top face adapted to engage the inclined face on the under side of the jaw, to operate in the manner set forth, for the purposes stated.

5. An improved car coupling comprising a draw head having a cavity in its front face and an angular space A² and a shoulder A³ in said cavity, a pin hole in the top and a pin hole in the bottom intersecting said cavity 115 and said pin holes forming an acute angle as set forth, a jaw pivoted to the draw head and having a rear extension provided with an angular end B² and a shoulder B³, an inclined under side and an integral pin-guard C and a jaw locking pin D having a projection D² at its top portion and a projection D³ at its 120 lower portion and an inclined top face on the said projection D³, arranged and combined to operate in the manner set forth for the purposes stated.
